INVENTOR.

Charles R. Birdsey

BY *Langdon Moore.*

ATTORNEY.

UNITED STATES PATENT OFFICE.

CHARLES R. BIRDSEY, OF HINSDALE, ILLINOIS, ASSIGNOR TO UNITED STATES GYPSUM COMPANY, OF CHICAGO, ILLINOIS, A CORPORATION OF ILLINOIS.

REINFORCED PLASTER WALL BOARD.

Original application filed January 13, 1921, Serial No. 437,062, now Patent No. 1,643,801, dated September 27, 1927. Divided and this application filed April 19, 1922. Serial No. 555,627.

My invention belongs to that general class of inventions relating to the production of plaster board or plaster wallboard and more particularly to an improved reenforced plaster wallboard, the method and apparatus for producing which is set forth in my prior application Serial No. 437,062, filed January 13, 1921, Patent No. 1,643,801, Sept. 27, 1927 and of which this is a divisional application.

10 The invention has among its objects the production of an improved wallboard, the edges of which are reenforced to prevent the crumbling or breaking away of the plaster body between the cover sheets.

15 To this end my invention consists in the novel construction, arrangement and combination of parts herein shown and described, and more particularly pointed out in the claims.

20 In the drawings, wherein like reference characters indicate like or corresponding parts—

Figure 1 is a view in perspective, with parts broken away, of my improved board showing 25 the longitudinal and transverse edges.

Figure 2 is a sectional view, taken transversely through the board, with parts broken away, illustrating the reenforced edges.

Plaster boards of various types have been 30 heretofore manufactured, some with what may be termed "raw" or "unbound" edges, and others with "bound" edges, the board proper consisting of a body of plaster or like material provided with covering sheets on the

35 two faces. Some types of boards have been manufactured in which sheets are imbedded in the body or the body made up of alternate sheets of imbedded covering material and plaster. A distinction is now being made.

40 between plaster board, which takes the place of laths and must receive a coat of plaster before papering or painting and plaster wallboard which takes the place of both laths and plaster that may be nailed in place and be

45 ready to receive a coat of paint or be papered. Among the requisites of plaster wallboard are uniformity of thickness, uniformity of width, and uniformity of the longitudinal edges, so that when the wallboards are nailed to the studding an even outer surface is presented.

In carrying out this invention, the plaster, or like material, body 1 is contained between

the cover sheets 2 and 3 of paper or fibrous material with the longitudinal edges raw or unbound. While it is preferable to provide 55 cover sheets of the exact width desired to produce a board of uniform width, it is not essential to this invention which relates particularly to the reenforcement of the edges.

The paper or fibrous cover sheets give the 60 tensile strength to the board and when nails are driven through the covering and body adjacent the longitudinal edges, as is necessary to secure the board to the studding, the body being frangible will break or crumble at the

65 open edges between the cover sheets which weakens the attachment to the studding, also during transportation blows received on or near the edges will produce the same result, so that the abutting edges of the board when 70 in place will be uneven. To overcome this

defect in the raw edge board and prevent this 75 crumbling of the body, one or more strengthening strips of paper or fibrous material, preferable of the same character as the cover sheets, are provided in the body between the cover sheets. As illustrated, two of the strips

80 4 and 5 are preferably employed which are imbedded in the body and extend from the exterior of the edges of the body a sufficient distance towards the center to hold the body together when a nail is driven there through the adjacent edge and reenforce it to resist 85 blows or shocks received during handling and transportation.

85 Since the plaster or like material forming the body adheres or bonds to the cover sheets and the inserts or reenforcing strips are of like material the body will adhere or bond to them so that from top to bottom sheet there 90 will be along each longitudinal edge alternate layers of fibrous material separated by alternate layers of plaster or like material. While the edges of the board are reenforced, yet the main body of the board is not divided or 95 separated as in the case of wide sheets inserted between the cover sheets, the portions of each cover sheet between the inserts or strips at the edges being connected with the body and through the medium of the body 100 to each other. This reenforced plaster board may be termed a wallboard in the true sense as the reenforcement at the edges insures uniformity of the edges and a slight crumbling

of the body between any of the reenforcing strips and cover sheets will not materially affect the strength or appearance of the edge.

What I claim as new and desire to secure by Letters Patent is:

1. A fabricated board comprising a body of plastic material and facing sheets of fibrous material, and having independent narrow insets of fibrous material and plastic material between the facing sheets only at the side edges of the board, for the purpose specified.
2. A fabricated board comprising a body of plastic material and facing sheets of fibrous material, and having independent narrow insets of fibrous material and plastic material between the facing sheets only at the side edges of the board for the purpose specified, said insets being composed of alternate narrow strips of fibrous material and 20 plaster.
3. A plaster board comprising a plaster body having covering sheets at each side thereof, and independent, segregated reenforcing strips imbedded in the body at the edges 25 thereof between said covering sheets.
4. A plaster board comprising a plaster body having covering sheets at each side thereof, and a plurality of independent reenforcing strips imbedded in the body at each-

of the side edges thereof between said covering sheets.

5. A plaster board comprising a body of plastic material and cover sheets of fibrous material bonded to the body on opposite sides thereof, and having independent narrow reenforcing strips of fibrous material extending inward from the edges into the body of plastic material and bonded thereto separated from each other and from the cover sheets by a substantial amount of the plastic 40 material forming the body.

6. A fabricated board comprising a body of plastic material having facing sheets of fibrous material, and having independent insets of fibrous material between the facing 45 sheets at the side edges of the board, said insets being separated from each other and from the facing sheets by layers of plaster.

7. A plaster board comprising a body of plastic material and cover sheets of fibrous 50 material adhering to the body on opposite face sides thereof, and having narrow reenforcing strips of fibrous material extending inwardly from the edges into the body of plastic material and separated from the cover 55 sheets by layers of plaster.

CHARLES R. BIRDSEY.
